UNITED STATES PATENT OFFICE.

THEODOR LUDOLPH HOLLE, OF ST. LOUIS, MISSOURI.

REGENERATOR FOR METALLURGICAL FURNACES.

1,076,426.

Specification of Letters Patent.

Patented Oct. 21, 1913.

Application filed January 18, 1913. Serial No. 742,924.

To all whom it may concern:

Be it known that I, THEODOR L. HOLLE, a subject of the Emperor of Germany, residing at St. Louis, in the State of Missouri, have invented certain new and useful Improvements in Regenerators for Metallurgical Furnaces, of which the following is a specification, reference being had to the accompanying drawings.

10 This invention relates to regenerators for metallurgical furnaces and has for its primary object to provide improved means for preheating the air or gas which is admitted to the furnace, and thus maintaining a sufficiently high degree of heat within the furnace for the reduction of the metals.

Another object of my invention is to provide in a regenerator of the above type, alternately arranged gas and air flues whereby the products of combustion travel through a circuitous course from the furnace to the stack and thus heat the incoming air which is moving in an opposite direction through the adjacent flues for mixture with the oil or fuel gas which is admitted to the furnace.

Still another object of the invention is to produce a regenerator so constructed that a relatively large number of flues may be arranged in a comparatively restricted space.

A further object of the invention is to provide structural units of novel design to permit of the construction of the flues of the regenerator of any desired capacity.

35 Still another object of the invention is to provide a regenerator for metallurgical furnaces which is of comparatively simple and economical construction and which will maintain a maximum heat temperature from a minimum consumption of fuel.

With the above and other objects in view as will become apparent as the description proceeds, the invention consists in certain constructions, combinations and arrangements of the parts that I shall hereinafter fully describe and claim.

For a full understanding of the invention, reference is to be had to the following description and accompanying drawings, in which—

Figure 1 is a side elevation of a metallurgical furnace provided with my improved regenerator; Fig. 2 is a top plan view thereof; Fig. 3 is a section taken on the line 3—3 of Fig. 5; Fig. 4 is a section taken on the line 4—4 of Fig. 3; Fig. 5 is

a section taken on the line 5—5 of Fig. 3; Fig. 6 is a section taken on the line 6—6 of Fig. 4; Fig. 7 is a section taken on the line 7—7 of Fig. 4; Fig. 8 is a section taken on the line 8—8 of Fig. 4; Fig. 9 is a section taken on the line 9—9 of Fig. 4; and Figs. 10 to 15 inclusive, illustrate the structural units used in building the regenerator flues.

Referring in detail to the drawings, 5 65 designates a metallurgical furnace which may be of any ordinary or approved construction and is provided with an outlet flue 6 into which the gases and products of combustion pass from the interior of the 70 furnace, and with an intake flue or passage 7 through which the air is admitted for mixture with the oil or fuel gas.

In the use of the cheaper grades of gas fuel in metallurgical furnaces, difficulty has 75 been experienced in maintaining a sufficiently high temperature in the furnace to produce a neutral or reducing action. The present invention is designed to overcome this defect and to preheat the air or gases 80 introduced into the furnace to a high degree. In order to produce this highly heated incoming current of air or gas, I provide a plurality of circuitous passages or flues alternately arranged for the passage of air and gas in opposite directions so that the outgoing products of combustion passing from the furnace to the stack will highly heat the flue walls, and the air traveling in the opposite direction through 85 the adjacent flues is heated in proportion to the temperature of said walls so that at the time said air enters the furnace it has attained such a high temperature that its mixture with the oil or fuel gas causes a 90 partial combustion, and thus maintains a maximum degree of heat within the furnace.

In carrying out my invention, I provide a regenerator which consists of front, end and side walls 8 of suitable height upon 100 which the cap wall 9 is supported. These walls are preferably constructed of fire brick or other heat resisting material. The outlet and inlet flues 6 and 7 respectively, of the furnace open into the top of the regenerator at opposite ends thereof, the products of combustion being admitted from the outlet flue 6 into a chamber 10 which is separated from the air chamber 11 by a bridge wall 12. A plurality of longitudinal series of flues are arranged in superposed relation within the generator, the

alternate flues 13 serving as a passage for the gas while the remaining flues 14 provide a passage for the incoming air. It will be noted as indicated by the arrows in Fig. 7 that the air and gas travel in opposite directions. The upper tier of flues have their top walls constructed of the building blocks or units 15 shown in detail in Figs. 10 and 15, and these 10 top walls of the air flues 14 at their forward ends terminate short of the bridge wall 12, to provide openings 16 affording communication between said air flues and the chamber 11. The rear ends of these walls 15 are suitably mounted and secured upon the rear vertical wall 8 of the generator. The upper walls of the remaining flues in the uppermost tier, however, extend at their forward ends through openings 17 provided 20 in the lower edge of the bridge wall 12. The blocks 15 are channeled or rabbeted at their opposite longitudinal edges, as indicated at 18, to receive the upper and lower edges of the side wall blocks 19 of the flues. 25 These side wall blocks have their vertical end edges rabbeted as shown at 20 so that when assembled they will form a lap joint as clearly shown in Fig. 7. The upper walls of the remaining tiers or flues are alternately spaced from the front and rear end walls of the structure as shown in Fig. 5 and these wall blocks are of the form illustrated in Figs. 13 and 14 of the drawings. The block 21 which is provided with the 30 ribs 22 upon its opposite faces is used at one terminal of the wall which is spaced from the end wall of the regenerator as shown in Fig. 4 to afford communication between the superposed series of flues. The 35 remaining upper wall blocks of the lower flues are of the form shown in Fig. 14 and are designated by the numeral 23.

It will be observed that the ribs on the blocks 21 terminate short of one end of 45 said blocks while the longitudinal ribs 24 provided upon opposite faces of the blocks 23 extend the entire length thereof. These ribs support the vertically disposed blocks 19 which are arranged between the upper 50 and lower wall blocks 21 and 23, the opposed ribs on adjacent blocks being in contact as shown in Fig. 3. At the ends of the upper and lower series of flues which 55 communicate, the vertical blocks 25 are arranged. These blocks as shown in Fig. 11 are of slightly different form from the blocks 19 and are rabbeted upon only one of their ends edges as shown at 26, the other edges of said blocks being set into 60 the vertical walls of the structure.

The bottom wall blocks 27 of the lowermost series of flues are of the ordinary rectangular form and are supported upon the foundation walls 28. At the forward 65 end of this lower series of flues, an air inlet

flue 29 is provided in the wall 8, and communicate with the adjacent flues of the lower series. A flue 30 is built along one side of the rear generator and the remaining flues of said lower series open into the flue 30 through the wall 8, the products of combustion finding an outlet through said latter flues to the furnace stack. 70

Referring now more particularly to Figs. 4 and 5 of the drawings, it will be observed that the gases enter the generator from the outlet flues 6 of the furnace and pass into the alternate flues 13 of the upper series. This waste gas travels to the rear end of said flues and passes downwardly into the corresponding flues of the next lower series, then forwardly and downwardly again to the next succeeding series of flues until they finally pass forwardly through the lower series of flues and out of the regenerator 80 through the flue 30. It will be obvious that this waste gas is gradually cooled by contact with the walls of these flues while on the other hand, said flues walls become highly heated, the temperature degree gradually 85 decreasing from the upper tier of flues to the lower tier. It will be apparent, however, that as the waste gases are retained within the generator for a comparatively long time, by causing the same to follow a circuitous 90 passage to the outlet flue, practically all of the heat units are extracted from the gas. The incoming cold air enters through the flue 29 into the alternate flues of the lower tier and also travels through a circuitous 95 passage in the same manner as the gas until the air finally enters the chamber 11 at the top of the generator from which it is drawn by the furnace draft up the intake flue or 100 passages 7 for mixture with the oil or fuel gas. It will be obvious that this incoming air will be highly heated by this contact 105 with the walls of the flues.

In Fig. 4 of the drawings, I have applied to the various portions of the several communicating flues, the approximate degree of 110 temperature which the flue walls will gradually attain. It will be noted therefrom, that the difference in temperature between the flue walls and the incoming air will be practically uniform, the air gradually increasing 115 in temperature as it passes upwardly through the flues.

From the foregoing, it is believed that the construction and several advantages of my 120 improved heat regenerator will be fully understood. By utilizing the waste gases to heat the incoming air, a maximum percentage of heat energy is obtained from a minimum consumption of fuel. It will also be 125 appreciated that by means of my invention, coarser grades of fuel may be used, thus minimizing the expense incident to the operation of the furnace. By providing the circuitous flues through which the oppositely 130

traveling air and heated gas pass, a very high temperature degree will be maintained in the furnace, without necessitating any increase in the consumption of fuel.

5 While I have herein described the preferred construction of the invention, it is to be understood that in putting the same into practice, I am not necessarily limited to the specific form and proportions illustrated 10 in the drawings, but reserve the right to make such alterations therein as may be deemed desirable, without departing from the spirit or sacrificing any of the advantages of the invention.

15 Having thus described the invention, what is claimed is:

1. A heat regenerator for furnaces comprising a plurality of circuitous flues, means for supplying air to the alternate flues at one 20 of their ends, said regenerator being provided with a gas receiving chamber located above said flues at one of their ends, the remaining flues opening into said chamber, a flue connecting said chamber with the furnace to supply waste gas thereto, said regenerator having a second chamber extending 25 over the flues for substantially their entire length, said air flues at their upper ends opening into said chamber, a bridge wall arranged between the top wall of the regen-

erator and the upper wall of said flues to isolate said chambers from each other, and a flue connecting said air receiving chamber with the furnace to supply heated air thereto.

35

2. A heat regenerator for furnaces, comprising a plurality of circuitous flues, means for supplying air to the alternate flues at one of their ends, the upper ends of said flues opening into a common air receiving chamber, a gas receiving chamber and a flue connecting the same with the furnace to supply waste gas thereto, a bridge wall separating said gas chamber from the air chamber, the remainder of said circuitous flues being 40 in communication at their upper ends with said gas chamber, a gas receiving flue communicating with the lower ends of said latter circuitous flues to conduct the waste gas from the generator, the gas and air traveling 45 in opposite directions through the adjacent circuitous flues, and a flue connecting said air receiving chamber with the furnace to supply the heated air thereto.

50

In testimony whereof I hereunto affix my signature in the presence of two witnesses.

THEODOR LUDOLPH HOLLE.
